[57] CLAIM

The ornamental design for a toilet or similar article, substantially as shown and described.

DESCRIPTION

FIG. 1 is a right side elevational view of a toilet or similar article embodying my new design, the left side being a mirror image of the right side shown;

FIG. 2 is a front elevational view thereof;

FIG. 3 is a top plan view thereof;

FIG. 4 is a real elevational view thereof; and

FIG. 5 is a bottom plan view thereof.

FIG. 1

FIG. 2

FIG. 4

FIG. 5
